UNITED STATES PATENT OFFICE

159,062

VISOR FOR MOTOR VEHICLES

Leon A. Hallstead, Buffalo, N. Y.

Application December 11, 1948, Serial No. 150,101

Term of patent 7 years

(Cl. D14—6)

To all whom it may concern:

Be it known that I, Leon A. Hallstead, a citizen of the United States, residing at Buffalo, in the county of Erie and State of New York, have invented a new, original, and ornamental Design for Visor for Motor Vehicles, of which the following is a specification, reference being had to the accompanying drawing, forming a part thereof.

Figure 1 is a perspective view of the visor for motor vehicles embodying my design, the portion of the vehicle to which it is attached being shown by dotted lines for illustrative purposes only. Figure 2 is a front view of the same. Figure 3 is a top plan view thereof.

I claim:

The ornamental design for a visor for motor vehicles, substantially as shown and described.

LEON A. HALLSTEAD.
